UNITED STATES PATENT OFFICE

1,982,997

APPARATUS FOR CLEANING MACHINES

Willis Walter Linder, Salisbury, N. C.

Application June 6, 1931, Serial No. 542,595

2 Claims. (Cl. 15—20)

This invention relates to a method and means of cleaning machinery and comprises the disposition of a plurality of perforated pipes along selected portions of a selected machine or machines with a valve mechanism for admitting compressed air intermittently to said pipes so that a plurality of jets of compressed air will be forced through said perforations in said pipes to strike against selected portions of a machine to remove therefrom lint and other foreign particles which may collect thereon.

This invention is shown as being applied to a spinning frame and a warping machine, but I desire it to be understood that this method and means may be applied to any type of machinery wherein it may be applicable for removing any kind of loose light particles therefrom which can be removed by the use of jets of compressed air.

I am aware that heretofore various attempts have been made in the cleaning of machinery, and especially textile machinery by mounting thereon stationary fans, also traveling fans for moving back and forth over the machine, also traveling fans on an endless track for passing successively over the machines at predetermined times, together with various other mechanisms and embodiments for cleaning machinery, but so far as I am aware it is new to place along selected portions of machinery one or more perforated pipes with valve mechanism for feeding intermittently to the pipe or pipes a compressed fluid such as compressed air for blowing from the machinery any foreign particles which may collect thereon.

Heretofore, perforated pipes have been employed for conducting compressed air or other fluid for causing the impinging of the jets of compressed air through the perforations on certain objects in a continuous stream for cleaning the same. It is evident that the continuous operation of such a compressed air plant would not be economical and would therefore be impractical, but with the embodiment as shown in the drawings, I have devised means whereby the compressed air may be allowed to pass intermittently through a system of perforated pipes for causing a plurality of jets of compressed air to impinge on the selected portions of the machinery, for removing lint and other particles from the machinery, which is just as efficacious and in certain instances, more so than if a continuous stream were employed and much more economical.

An object of this invention is to provide a method and means for conducting compressed air

to selected portions of machinery by means of perforated pipes with said perforations being suitably arranged to direct the jets of air against selected portions of the machine, and in the drawings, I have shown opposite sides of the machine equipped with longitudinally extending pipes with perforations therein, in some instances, directed towards each other, but in staggered relation so that one jet of air will not interfere with the jet on the opposite side of the machine in case both of the jets are in operation at the same time.

This invention contemplates the idea of supplying the jets of air either simultaneously to both sides of the machine or alternately for allowing the pipes on one side to be filled with compressed air while the pipes on the other side are not so filled, and then reversing the operation and in this way, opposite sides of the machine will be treated alternately to remove therefrom lint and other particles and to obviate any possibility of the jets in the pipes on one side interfering with the efficiency of the jets in the pipes on the other side of the machine.

Also my invention contemplates a system of piping in a manufacturing plant whereby compressed air may be suitably conducted throughout the manufacturing plant with connections thereto for treating a great number of machines from a single source of compressed air with a single valve mechanism for distributing and controlling the passage of compressed air to the various portions of the manufacturing plant, and I desire it to be understood that in a system such as shown in Figure 17, a plurality of control valves may be employed at various points throughout the piping system if desired. Also the piping may be reduced as its length increases, if found desirable.

Some of the objects of the invention having been stated, other objects will appear as the description proceeds when taken in connection with the accompanying drawings, in which—

Figure 1 is a vertical sectional view taken through a spinning frame and showing my invention as applied thereto;

Figure 2 is a side elevation of a spinning frame with the central portion broken away showing the invention in one of its forms applied thereto;

Figure 3 is a side elevation showing a portion of a warping machine with my invention applied thereto;

Figure 4 is a longitudinal sectional view of a form of control valve;

Figure 5 is an end elevation of another form of control valve;

Figure 6 is a longitudinal sectional view taken along line 6—6 of Figure 5;

Figure 7 is an end elevation of another form of distributing valve looking from the left hand side of Figure 8;

Figure 8 is a longitudinal sectional view taken along the line 8—8 in Figure 7;

10 Figure 9 is a modified form of valve showing a slide valve arrangement for controlling the passage of compressed air to the various pipes on the machinery;

Figure 10 is a longitudinal sectional view taken 15 along the line 10—10 in Figure 9;

Figure 11 is a transverse cross sectional view taken along the line 11—11 in Figure 9;

Figure 12 is a plan view showing means for cutting off the source of compressed air from 20 the distributing valve when the machine with which it is associated is idle;

Figure 13 is a plan view of another modified form of the distributing valve;

25 Figure 14 is a cross sectional view taken along the line 14—14 in Figure 13;

Figure 15 is a longitudinal section taken along the line 15—15 in Figure 14;

Figure 16 is a longitudinal section taken along the line 16—16 in Figure 14;

Figure 17 is a schematic diagram of a piping arrangement for a manufacturing plant having a plurality of machines therein;

Figure 18 is a schematic view showing the disposition of the perforations in opposed pipes on opposite sides of a machine.

Figure 19 is an enlarged cross sectional view taken through one of the pipes having a single row of perforations therein;

Figure 20 is an enlarged cross sectional view taken through one of the pipes having a plurality of rows of perforations therein for directing the air in a plurality of directions from said pipe;

Figure 21 is a diagrammatic view showing the direction of travel of the jets of air for pipes 33 and 33a.

Referring more specifically to the drawings, the numeral 10 indicates a spinning frame, having conventional features including an upper creel board 11 and central and lower boards 12 and 13, said boards supporting bobbins 15, the frame having top portion 16 adapted to support a plurality of roll stands 17, having suitable drawing rolls therein through which the yarn is passed in the drawing operation.

The spinning frame has conventional thread boards 18 having eyes 19 therein for guiding the ends 20 from the bobbins through the drawing rolls to the bobbins 21 which bobbins have a ring rail 22 in association therewith, said bobbins being supported and driven on a spindle rail 23. The boards 11 and 12 are supported by suitable upright centrally disposed supports 24 on which collars 25 are mounted for supporting the boards, and the base of said supports 24 is secured in a suitable collar 27.

70 For the purpose of blowing lint and other particles from the above described apparatus, I mount longitudinally on the machine a plurality of perforated pipes 30, 31, 32, 33, 34 and 35 on one side of the machine, and on the other side of the machine, similar perforated pipes 30a, 31a, 32a, 33a, 34a and 35a are similarly disposed.

Pipes 30 and 30a are suitably supported above the top creel board 11 by means of brackets 36

and 36a while brackets 37 and 37a which normally support the guide rods are employed for the perforated pipes 31 and 31a respectively, which replace such usual guide rods and perform their function. To board 12, I secure brackets 39 and 39a respectively which support pipes 32 and 32a. Pipes 33 and 33a are supported by brackets or in a specially made collar which is similar to the conventional collar heretofore employed except that it has two longitudinally disposed cavities on the upper surface thereof in which pipes 33 and 33a are supported. Pipes 34 and 34a are supported beneath the thread board by any suitable means such as brackets 40 and 40a; whereas, no means are shown for supporting pipes 35 and 35a as it is evident that any suitable means may be employed for supporting these pipes.

While I have enumerated the various pipes and their location with respect to the conventional parts of a spinning frame, it is evident that I do not desire to be limited to the particular location or to the particular number of pipes, as any suitable number may be employed and may be disposed at locations which are found to be most efficient in operation.

The arrows in Figure 1 indicate the direction of flow of the jets of air against the parts of the machine.

In Figure 19, I show a perforation 42 which is adapted to direct the air in pipes 30 and 30a, for example, against the creel board 11, as indicated by the arrows and, of course, after striking against the creel board, the air will be deflected along the surface of the creel board, 110 where it spreads fanwise as the distance from the orifice increases. In the case of pipes 33 and 33a, the jets of air in one pipe will go toward the other pipe, but may be in staggered relation as shown in Figure 18 and will direct the air angularly downwardly. The staggered position of perforations may or may not be employed under certain conditions.

These downwardly and laterally directed jets of air are disposed at an angle and strike beneath 120 the companion pipe and spread out as above described. In Figure 21 the direction of jets is shown diagrammatically. It is to be noted of this latter pair of pipes that their jets overlap transversely of the machine, so that areas between the pipes are also cleaned.

In the case of pipes 32 and 32a and possibly in case of others such as pipes 34 and 34a, there may be two rows of jets if desired as shown in Figure 20 for directing the jets of air against 130 two or more portions of the machine.

In case of pipes 35 and 35a, the jets of air may be directed toward each other in staggered relation as shown in Figure 18 against the floor for removing lint from beneath the machine, or the 135 staggered relation may not be used.

Suitable means are employed for allowing compressed air to flow into the perforated pipes, and in Figure 2, there is shown one means of accomplishing this result. Pipes 30 and 31 are 140 tapped into the pipe 45 which leads to a manifold 46, but pipe 32 leads directly to the manifold as do pipes 33, 34 and 35.

Although the manifold is not shown on the other side of the machine, pipes 30a to 35a inclusive are likewise connected to another manifold similar to 46 but not shown.

Leading to manifold 46 is a pipe 47 which leads to a distributing valve mechanism 48 which has a pipe line 49 leading thereto from a source of 150

compressed air 50. Pipe 47a is shown as leading from another portion of the distributing valve to the manifold corresponding to 46, but serving pipes 30a to 35a inclusive (see Figures 5 and 6).

5 Distributing valve mechanism 48 comprises a casing 51 to which is secured a plate 52 by any suitable means such as stud bolts 53, said plates having a central projection 54 serving as a bearing for a rotatable disk 55 which has a circular 10 raised portion 56 covering ports 57 and 58 for pipes 47 and 47a respectively. This disk has a port 59 therein through which compressed air in chamber 50 may pass when port 59 coincides with port 58 or port 57 as the case may be.

15 Disk 55 is slidably mounted on a key 60, this key being set in shaft 61, which shaft 61 extends into a projection 63 on disk 55 which projection extends into a cavity in projection 54 for rotative movement therein. If desired, ports 57 and 58 20 may be in the form of a slot, and if desired ports 59 may be also in the form of a slot, said form being indicated by reference character 64 in Figure 5.

25 Casing 51 has a projection 66 thereon in which is rotatably mounted shaft 61, and a compression spring 67 surrounds shaft 61, between the inside of casing 51 and projection 68 on disk 55, to force disk 55 against cover 52 when the device 30 is inoperative as it is evident that the compressed air in itself would hold disk 55 against cover plate 52 when in operation, but by providing this spring it causes the ports 57 and 58 to be closed when compressed air is first admitted to the cavity 50.

35 Projection 66 has a packing box 70 therein in which suitable packing may be placed, and a packing gland 71 is threadably secured on the interior of projection 66 with shaft 61 being rotatably mounted in said packing gland and in casing 51, and projecting to the exterior thereof, and in close proximity to packing gland 71, and fixedly secured to shaft 61 is a ratchet wheel 73 which has a guard 74 which is adjustably mounted around projection 66 and packing gland 40 71 and is held in adjusted position by means of a set screw 75. The guard portion extends over the periphery of ratchet wheel 73 for limiting the amount of rotative movement which is imparted to said ratchet wheel by a lever 77 which 45 is loosely secured on shaft 61 and confined thereon by means of a nut 78.

50 Lever 77 has a pawl 80 which is pivotally mounted on bolt 81. Said pawl 80 has a weighted portion 82 for holding the other end of pawl 80 in engagement with the teeth of ratchet wheel or against guard 74. Oscillatory movement may be imparted to lever 77 by any suitable means such as a cam 83 secured on one of the gears in the railway head of the spinning frame so that an oscillation will be imparted to the shaft, and after the pawl 80 rides over guard 74, it will engage teeth of ratchet wheel 73 and move shaft 61 and disk 55 thereon.

55 It is seen by the arrangement described that when port 59 registers with port 58 that compressed air will be admitted to pipe 47a and compressed air will be admitted to a manifold similar to manifold 46 which will allow compressed air to pass simultaneously through pipes 30a to 35a 60 inclusive and strike against a plurality of portions on one side of a machine, and then when port 59 travels to a point where it will coincide with port 57, compressed air will be passed into pipe 47, and into manifold 46 and out through all of pipes 30 to 35 inclusive to cause jets of air 65

to strike against a plurality of portions along the other side of the machine.

The above described operation for a spinning frame may be carried out on any other type of machinery such as warping machines, roving frames, fly frames, and all kinds of drawing, spinning, and winding machinery, and in fact any type of machine on which loose particles may collect and for which this system of perforated pipes might be applicable for removing these loose particles therefrom.

70 In Figure 3, I have shown how the invention may be applied to a warping machine, which warping machine is indicated by reference character 90, with bobbins 91 and 92 from which the thread is drawn through combs 93 and 94 in conjunction with suitable rolls and thru drop wires 100e and 100f and wound on warping beam 95. In this application, I show perforated pipes 96 and 97 for comb 93, the direction of jets of air 75 being indicated in dotted lines and I also provide pipes 98 and 99 for comb 94 with the jets of air being indicated as to direction. It is evident that additional perforated pipes may be applied to this type of machine if desired, an example 80 being, perforated pipes 100a and 100b for directing jets of air against the drop wires 100f either simultaneously or alternately, and perforated pipes 100c and 100d for directing jets of air against drop wires 100e. These jets of 85 compressed air will also keep clean the other parts of the machine cooperating with the drop wires, particularly the stop motion mechanism. It is also evident that pipes such as 100a, 100b, 100c and 100d may be installed on looms and 90 all other machines having drop wires on yarns.

95 In Figure 4, I show another form of distributing valve for supplying compressed air to the systems of pipes heretofore described in which the valve casing is indicated by reference character 100, which casing has a cover plate 101 secured thereto by any suitable means such as stud bolts 102.

100 Cover plate 101 has a circular hole 115 therein in projection 107 which is covered by a nut 103 which, likewise, has a circular centrally disposed hole therein, and this nut has an exterior cavity which is interiorly threaded for the reception of a packing gland 104, and in which a shaft 105 is rotatably mounted which shaft has one end 105 thereof fixedly secured in a rotating valve member 106. Nut 103 is threadedly secured on projection 107 of cover plate 101, and this nut 103 has the extension 108 thereon on which is mounted for oscillation lever 109 which lever is adapted 110 to be oscillated by any suitable mechanism such as that shown for oscillating lever 77 in Figure 5. This lever has a bolt 110 therethrough on which is pivotally mounted a weighted pawl 111 similar to pawl 80 in Figure 5. This pawl 111 is adapted to engage ratchet wheel 112 which is fixedly secured on shaft 105 by any suitable means such as having the portion of shaft 105 which penetrates ratchet wheel 112 of smaller 115 cross sectional area than the remaining portion of the shaft with a nut 113 threadably secured on the end of the shaft for holding the ratchet wheel in position. A compression spring 114 surrounds shaft 105 and is disposed in the cavity 115 in projection 107, and one end of this spring 114 rests against the interior surface of nut 103; whereas, the other end presses against valve 106 for seating the same against the seat 117 in casing 100. Casing 100 has a supply pipe 49 in one side thereof leading to a cavity 118, and 120

125

130

135

140

145

150

on the other side of casing from the entrance of pipe 49 two ports 120 and 121 in which pipes 122 and 123 are secured, one of said pipes being adapted to be led to one set of perforated pipes 5 on a machine, and the other pipe being adapted to be led to another set of pipes located in another portion of the machine, similar to the showing in Figures 1 and 2.

Valve 106 has passageways 125 and 126 there- 10 through, these passageways being in different vertical planes in the valve 106 and being angularly disposed to each other, passageway 125 being adapted to allow compressed air to flow from supply pipe 49 into pipe 123; whereas, passageway 126 is adapted to allow compressed air to flow from supply pipe 49 into pipe 122 as valve 106 is rotated. Valve 106 has in the other side thereof from shaft 105, another shaft 128 fixedly secured therein which penetrates the closed end 15 of casing 100 in which it is rotatably mounted.

In Figure 12 there is shown means whereby the compressed air can be cut off from the valve mechanism when the machine is in inoperative position, and in this view a portion of the end 20 of a spinning frame is shown in which main drive shaft 130 has a loose pulley 131 thereon and a tight pulley 132 with a slideable rod 133, which is connected to the shipper lever, not shown, of the machine. This rod 133 has a guide 134 fixedly 25 secured thereto with an enlarged opening 135 therein through which belt 136, for driving the machine, passes after passing around pulley 131 or 132 as the case may be and going to a suitable 30 source of driving power, not shown.

Connected to rod 133 is an arm 137 to which is 35 connected a link 138 which is connected with a sliding valve, the details of which are not shown, but the casing is indicated by reference character 139. To one side of valve 139 supply pipe 140 is connected, and from the other side of valve 40 139, pipe 49 is led to the valve mechanism which is employed for distributing the compressed air to the perforated pipes on the machine. In the 45 position shown, the belt is on the loose pulley, and the machine is inoperative and, therefore, valve 139 is closed to prevent air from being conducted through pipe 49 into distributing valve, and, of course, it is evident that when the rod 133 is moved from this position to cause belt 136 to 50 engage the tight pulley 132, then valve 139 will be opened and compressed air will be admitted to the distributing valve.

In Figures 9, 10 and 11, a form of sliding valve 55 is shown, which may be used under certain conditions for distributing the compressed air to the two systems of pipes. This valve mechanism is indicated broadly by reference character 141 and has a cavity 142 therein, the casing in which 142 occurs being indicated by reference character 143 60 which casing has a cover plate 144 thereon secured by any suitable means such as stud bolts 145. At one end of casing 143 a projection 146 occurs in which a passageway 147 is provided with two inlets thereto in case two should be needed 65 and in the drawings, one of these inlets is shown closed by a plug 148 and the other inlet has connected thereto the supply pipe 49.

In the bottom of casing 143 are ports 150 and 70 151 in which pipes 152 and 153 are secured, said pipes being adapted to conduct compressed air to two different portions of the machine such as the two manifolds 46 in Figure 2, or if desired, to the piping arrangement shown in Figure 17.

Slidably mounted in the bottom of the casing 75 143 and covering one port at a time is a plate

member 155 which has two upwardly projecting spaced lugs 156 and 157 having vertically disposed aligned slots 158 and 159 therein, said lugs forming a space 160 therebetween and in slots 158 and 159 is mounted a shaft 161 which has a collar 162 secured thereon between the lugs 156 and 157. Casing 143 has a projection 168 thereon thru which shaft 161 passes, said projection having a space 169 for the reception of packing which packing is confined in position by means of a packing gland 170 threadably secured on the interior of projection 168 and surrounding shaft 161 and forming a bearing portion for said shaft. Shaft 161 has collars 172 and 173 adjustably secured thereon on opposite sides of an arm 174 which arm is secured to a member 175, which is adapted to be reciprocated by any suitable means as by the traverse rail of a roving or spinning frame, for moving plate 155 back and forth to cover alternately ports 150 and 151.

In Figures 13 to 16 inclusive, another form of sliding valve is shown, which is very similar to the valve just described, except that manifolds are provided in the casing of the valve instead of leading pipes therefrom to separated manifolds.

In the modified form shown in Figures 13 to 16 inclusive, a casing is indicated by reference character 180 which casing has manifolds 181 and 182 in the lower portion thereof to which respectively occur ports 183, 184, 185, 186 and ports 187, 188, 189 and 190, manifold 181 having in the upper portion thereof communication with valve chamber 191 by means of a port 192, whereas, manifold 182 has communication with chamber 191 by means of a port 193. A sliding valve member 194 is mounted in chamber 191, said valve 194 having upwardly projecting spaced members 195 and 196, having aligned slots vertically disposed therein in which rod 197 is mounted by means of a collar 198 fixed on said rod between the projections 195 and 196. This rod projects out of said casing through projection 199 having a packing chamber 200 therein and a packing gland 201 secured to projection 199 by any suitable means such as by threading or by stud bolts 202, this packing gland forming a bearing portion for shaft 197.

Casing 180 has two ports 203 and 204 leading from opposite sides into chamber 191, one of these ports being adapted to have connected thereto a source of compressed air and the other of said ports may be plugged unless two separate sources of compressed air should be desired to be led thereto so that in case of failure of one source of compressed air, that another would be available for uninterrupted operation of the system. Casing 180 has a suitable cover 205 secured over the open end thereof by any suitable means such as stud bolts 206, and this casing has a port 210 therein to which may be connected another source of compressed air or it may be plugged if desired.

Ports 183 to 186 may have mounted therein pipes for conducting a compressed fluid to selected portions of a machine, while other pipes may be secured in ports 187 to 190 and conducted to other portions of the machine.

Heretofore, the description has been limited largely to describing the application of the system of perforated pipes to a machine, and of course, it is evident that this system may be applied to a plurality of machines as shown in Figure 17, in which the rows of machines are indicated by the capital letters A, B, C and D. One form of installation of this type may comprise two pipes 220 and 221 leading from distributing valve or manifold. Pipe 220 has con-

80

145

150

5 nected thereto branches 222, 223 and 224, and pipe 221 has connected thereto pipes 225 and 226. These pipes 222 to 226 inclusive are led down between the rows A, B, C and D of the machines, and pipe 222 has branches 227, 228 and 229 leading to one side of row A of the machine, whereas, pipe 225 has pipes 230, 231 and 232 leading to the other side of row A of the machine. Pipe 225 also has branches 233, 234 and 10 235 leading to one side of row B of the machine, whereas pipe 223 has branches 236, 237 and 238 leading to the other side of row B of the machine.

Pipe 223 also has branches 239, 240 and 241 leading to one side of row C of the machines, 15 while pipe 226 has branches 242, 243, and 244 leading to the other side of row C of the machines. Pipe 226 has branches 245, 246, and 247 leading to one side of row D of the machines, and pipe 224 and branches 248, 249 and 250 leading to the other side of row D of the machines. Each of the branches from said pipes has a plurality of pipes 252 connected thereto which are disposed along various portions of the machines and one form of the disposition of these pipes is 25 shown in Figure 1.

By this arrangement it is seen that blasts of air will be passed through the perforated pipes running along selected portions of the machine on one side of the rows A, B, C and D by compressed 30 air being admitted through pipe 220 and its branches, and then as the distributing valve moves to allow compressed air to pass out of its other port, pipe 221 will be charged with compressed air and the other side of the rows of 35 machines will receive the jets of compressed air for cleaning the same, and in this way there will be no interference between the jets of air issuing from the pipes on one side of the machine against the jets issuing from pipes on the other side of 40 the machine.

Heretofore, the explanation has been largely devoted to alternately treating opposite sides of a machine or portions of a machine with compressed air, while other portions of the machine 45 would not be operated upon, and in the distributing valves heretofore described, only two ports have been shown for operating upon two sets of perforated pipes by allowing compressed air to be passed to the two sets of perforated pipes. In 50 case a machine should be equipped with a plurality of perforated pipes and the alternate application of compressed air should not be desired to be limited to two sets of pipes, it is evident that a great number of pipes can be passed to various 55 portions of a machine for progressive operation of the mechanism by allowing compressed air to enter, first one pipe and then another, and another and so on until the cycle has been completed, and in order to provide for an installation 60 of this kind, I have shown in Figures 7 and 8 a type of valve which may be used for this purpose.

In Figures 7 and 8 reference character 260 indicates a casing having a plurality of ports 261, 65 262, 263, 264, 265, 266, 267 and 268, and if desired, it is evident that this number of ports can be materially increased by a re-design of the casing 70 260. These pipes 261 to 268 inclusive may be led to various portions of a machine and connected to a system of perforated pipes for passing compressed air thereto. Casing 260 has a projection 270 thereon which is hollow and has a bearing 271 therein for the reception of a shaft 272 which shaft has a disk 273 fixedly secured thereon by 75 any suitable means such as a pin 274 penetrating

hub portion 275 of disk 273. Casing 260 is closed by a cover plate 276 secured thereto by any suitable means such as stud bolts 277. Cover 276 has a hub portion 278 having a cavity 279 therein for the reception of suitable packing, and in which cavity a packing land 280 is mounted and being secured in position by any suitable means such as stud bolts 281, said packing gland in association with the opening in cover 276 forming a bearing for another portion of shaft 272. Shaft 272 is driven by any suitable means for imparting rotation to the same. A suitable inlet pipe 49 is connected to the casing 260 and has communication with a cavity 282. Plate 273 has a perforation 283 therein which may be an elongated slot or a round perforation as desired, and this perforation 283 progressively coincides with ports 285 in which the pipes 261 to 268 respectively are mounted so that it is seen that as plate 273 is rotated that pipes 261 to 268 will be progressively traversed 95 and allow perforation 283 to coincide successively with the ports in which the pipes are mounted and cause compressed air to be passed through said pipes. Between hub 275 and inside surface of cover plate 276 a compression spring 269 is mounted loosely on shaft 272 which holds plate 273 against circular slot portion 259 on inside of casing 260.

In Figure 18 a diagrammatic view is shown in which pipes on opposite sides of a machine are 105 shown, and the arrows 286 and 287 respectively show the direction of the jets of air issuing from the perforations, it being evident that where pipes on opposite sides of a machine have their perforations directed toward each other even though 110 at a different angle, the perforations may be staggered to cause the jets of air to not interfere with each other and also to cause them to more thoroughly clean the entire machine.

In case of alternate charging of opposed pipes, 115 the staggered perforations 42a and 42b may or may not be used, as the perforations can be disposed in any suitable manner.

It is evident that a jet of air issuing from a 120 perforation will spread out fanwise and cover a much larger area than the size of the perforation. Also the perforations can have parallel sidewalls, as shown or can be varied as to the angularity of the sidewalls to suit different conditions.

In the drawings and specification, there has 125 been set forth a preferred embodiment of the invention and although specific terms are employed, they are used in a generic and descriptive sense only and not for purposes of limitation, the scope 130 of the invention being set forth in the appended 135 claims.

I claim:

1. An air cleaning apparatus for textile machinery of the character which deposits loose lint to the detriment of its successful operation, embodying a plurality of permanently fixed air distributing pipes arranged in opposition to each other and extending longitudinally of the textile machine, each air pipe being provided with a series of air exit ports directed to the parts of the 140 machine to be cleaned, a source of compressed air, a valve mechanism connected by a pipe to said air source and provided with a plurality of discharge ports and also a valve for controlling said discharge ports alternately, means for operating said 145 valve continuously during the operation of the textile machine, and pipe lines connecting said valve mechanism to said air distributing pipes whereby air is blown alternately from the opposed 150 distributing pipes.

2. In combination, a spinning machine or the like, a plurality of air pipes mounted in the machine and extending the length of the machine on both sides thereof, each of said pipes being provided with jet openings for delivering a multiplicity of small blasts of air into the atmosphere, these jet openings being arranged to direct said multiplicity of blasts upon the parts of the machine to be kept clear of lint deposits, and means for supplying air under pressure to the inlet ends of said pipes, said pipes being divided into two sets, said means for supplying air under pressure to said pipes being constructed to automatically supply the air to the two sets of pipes successively. 80

WILLIS WALTER LINDER.
